UNITED STATES PATENT OFFICE.

GEORGE C. BREIDERT, OF CHICAGO, ILLINOIS, AND VERNE E. STARKS, OF CLEVELAND, OHIO, ASSIGNORS TO ILG ELECTRIC VENTILATING COMPANY, OF CHICAGO, ILLINOIS, A CORPORATION OF LOUISIANA.

PORTABLE VENTILATING OUTFIT.

Application filed September 23, 1922. Serial No. 590,194.

To all whom it may concern:

Be it known that we, GEORGE C. BREIDERT and VERNE E. STARKS, citizens of the United States, residing, respectively, at Chicago, in the county of Cook and State of Illinois, and Cleveland, in the county of Cuyahoga and State of Ohio, have invented certain new and useful Improvements in Portable Ventilating Outfits, of which the following is a specification.

This invention relates to ventilating apparatus, and has for its main object to provide a simple, inexpensive and efficient portable ventilating appliance which can readily be applied to the windows of residences and other buildings to draw off foul air from the interior or induce fresh air from the outside, without involving any alteration or defacement of the window structure.

Another object of the invention is to provide an appliance of the character specified that shall be capable of adjustment to fit varying heights of window frame heads, and varying widths of window openings.

A further object is to provide a unitary ventilating structure for application to windows wherein an electrically driven fan, a switch, a plug socket, circuit lines, suspension means and the bottom closure member may all be mounted on a panel adapted to fit the upper portion of a window frame. Other objects and attendant advantages of the invention will be understood by persons skilled in the art from the following detailed description, taken in connection with the accompanying drawing in which we have illustrated one practical and approved embodiment of our invention in association with two means or instrumentalities for suspending the same from the head of the window frame and wherein—

Fig. 1 is a front elevation showing our portable ventilator applied to a window;

Fig. 2 is an edge elevation partly in vertical transverse section;

Fig. 3 is a fragmentary detail view illustrating a suspending device applicable to inset window frame heads;

Fig. 4 is a perspective elevation of one of the suspension hooks;

Fig. 5 is a front elevation of a modified form of portable ventilator that is adjust-

able widthwise to fit varying widths of window openings;

Fig. 6 is a view similar to Fig. 2, showing the ventilator of Fig. 5 applied to a window frame;

Fig. 7 is a top plan view of the frame shown in Fig. 5, partially broken away in section;

Fig. 8 is a front elevation of a lengthwise adjustable closure strip adapted to be secured to the top bar of the upper sash; and

Fig. 9 is an end elevation of Fig. 8.

Referring to the drawings, 5 designates as an entirety an ordinary box window frame, and 6 the head thereof. 7 and 8 designate the usual upper and lower counter-weighted sliding sash.

In the embodiment of the invention shown in Figs. 1 to 4 inclusive, 9 designates a flat panel of rectangular form and of slightly greater width than the window frame opening and designed to overhang the upper portion of the latter, said panel having a central circular opening 10, around which is secured a ring 11 carrying radial arms 12 in turn carrying a ring 13 which constitutes a holder and support for an electric motor 14, the armature shaft of which is equipped with a fan 15. The panel 9 is preferably made of sheet metal, and provided with marginal ribs or flanges 9' to stiffen the same.

On one corner of the panel (the lower right hand corner as herein shown) is mounted a switch 16; and on another corner (the upper right hand corner as herein shown) is mounted an ordinary plug socket 17. Circuit lines 18 from the plug socket 17 to the motor may be covered by suitable housing strips 19.

On the upper end of the panel are a pair of brackets 20 carrying set screws 21 that extend through slots 22 in the lower shank portions of a pair of hooks 23. As shown in Fig. 4 the free ends of the hooks 23 are preferably forked and pointed as shown at 23' to readily bite into the top of the window head 6 and thus securely support the ventilating outfit against danger of accidental dislodgement. The set screws 21 and slots 22 enable the appliance to be fitted to window heads of varying heights.

To the lower edge of the panel 9 is attached by hinges 24 a strip 25 of sufficient

width to span the space between the lower edge of the panel and the top of the lowered upper sash 7, as clearly shown in Fig. 2. Obviously the hinging of the closure strip 25 5 enables it to co-operate with the sash 7 without requiring the latter to be lowered to an exact position; and when the ventilator is not in use the upper sash may be raised without requiring the removal of the ventilator, the closure strip 25 merely swinging 10 upwardly out of the way.

In some building structures the frame head is inset or flush with the plaster wall, as shown at 6' in Fig. 3. To co-operate with 15 such a structure, in lieu of the suspension hook 23 a hinge 26 may be secured to the head 6', its depending leaf being slotted to receive the set screw 21' mounted in the bracket 20'. In this structure the ventilator is applied and removed by simply applying and removing the set screws 21'.

The structure hereinabove described employs a single panel of fixed dimensions and, of course, adaptable only to a window frame 25 opening of the same or a somewhat less width. In Figs. 5 to 9 inclusive we have shown another form of the invention employing a pair of relatively slidable panel sections, which adapt the device to windows 30 of considerable varying widths. In these views, 27 designates a vertically disposed sheet metal strip provided on its upper and lower edges with oppositely facing slide-ways or guides 28 and 29 respectively, which 35 are considerably extended on one side of the strip 27, as shown at 28' and 29'. Slidably mounted at their upper and lower edges in these guide strips are a pair of panel sections 30 and 31 which lie in a common vertical plane and, in the narrowest adjustment 40 of the panel, meet edge to edge in a joint indicated at 32, which joint, in the contiguous position of the panel sections, may be covered by a lap strip 33 attached to one of the 45 sections and overlapping the adjacent edge of the other. The fan, its plug, switch and circuit wires are mounted on one of the panel sections, preferably the larger section 30, substantially in the manner shown in 50 Fig. 1; and the suspension hooks 23' are attached to the outer ends of the two panels, respectively, in the manner and by means previously described. This construction enables the panel to be widened from the narrowest width shown in Fig. 5 to an extent 55 substantially equal to the width of the mounting strip 27.

The closure strip, instead of being hinged to the lower edge of the panel, as in the 60 constructions shown in Figs. 1 to 4 inclusive, is attached to the top bar of the upper sash. The strip is lengthwise adjustable, and comprises a pair of slidably interfitted horizontal strips 34 and 35 having on their 65 rear edges interfitting vertical flanges 34'

and 35', respectively. The strips 34 and 35 are attached at their ends to the window sash by screws 36. The closure strip is first adjusted lengthwise to the width of the particular window sash, and is then attached 70 to the latter by the means described, and when the panel is applied to the window, the upper sash is lowered until the free edge of the closure strip substantially registers with the lower edge of the panel. 75

From the foregoing it will be seen that the appliance of our present invention obviates the necessity of making permanent installations of ventilating fans on windows, which is a great advantage, especially in residences and the like where it may be desired to use the ventilator only occasionally or at special times. Its readily portable character enables it to be applied and connected up to a current circuit line with a minimum 80 of time and trouble, and as easily and quickly removed. 85

Manifestly the specific details of structure and relative arrangement herein shown and described may be variously changed without involving any departure from the substance of the invention or sacrificing any advantage or utility thereof. Hence, we reserve such modifications as fall within the spirit and purview of the appended claims. 95

We claim—

1. A portable ventilating appliance of the character described, comprising in combination a panel adapted to overhang a portion of a window opening and formed with an opening, a fan motor and fan mounted on said panel over said panel opening, and suspension hooks attached to said panel and at their free ends adapted to engage with the upper edge of the head piece of a window frame. 100

2. A portable ventilating appliance of the character described, comprising in combination a panel adapted to overhang a portion of a window opening and formed with an opening, a fan motor and fan mounted on said panel over said panel opening, and suspension hooks attached to said panel with capacity for vertical adjustment and formed with pointed free ends adapted to engage with the upper edge of the head piece of a window frame. 110

3. A portable ventilating appliance of the character described, comprising in combination a panel adapted to overhang a portion of a window opening and formed with an opening, a fan motor and fan mounted on said panel over said panel opening, means for removably supporting said panel on a window frame, and a closure strip movable relatively to said panel spanning the space between the lower edge of said panel and the top edge of a window sash. 120

4. A portable ventilating appliance of the character described, comprising in com- 125

- bination a widthwise adjustable panel comprising a pair of relatively slidable over-lapping sections and supporting and guiding means therefor, said panel adapt-
5 ed to overhang a portion of a window opening and itself formed with an opening, a fan motor and fan mounted on said panel over said panel opening, means for removably supporting said panel on a
10 window frame, and a lengthwise adjustable closure strip movable relatively to said panel spanning the space between the lower edge of said panel and the top edge of a
15 window sash.
5. A portable ventilating appliance of the character described, comprising in combina-
tion a widthwise adjustable panel comprising a pair of relatively slidable over-lapping sections and supporting and guiding means therefor, said panel adapted to overhang a 20 portion of a window opening and itself formed with an opening, a fan motor and fan mounted on said panel over said panel opening, means for removably supporting said panel on a window frame, and a length-
wise adjustable closure strip attached to the top bar of the upper window sash and spanning the space between the latter and the lower edge of said panel. 25
